UNITED STATES PATENT OFFICE.

JEAN HUBERT, OF PARIS, FRANCE.

SUSTAINING AND STEERING SURFACE FOR AIRCRAFT.

Application filed July 10, 1922. Serial No. 573,994.

To all whom it may concern:

Be it known that I, JEAN HUBERT, citizen of the French Republic, residing at Paris, France, have invented certain new and useful Improvements in Sustaining and Steering Surfaces for Aircraft, of which the following is a specification.

This invention relates to sustaining and steering-planes for air-craft.

10 It has for its purpose, primarily to provide such planes which shall be more resistant to the stresses imposed upon them and more easily assembled than those heretofore used.

15 The invention consists, chiefly, in constructing the plane of a number of elongated cells or cell-like members which are continuous in the direction of the spread of the plane, the plane being essentially constituted by these cells, and those cells which constitute the extrados and the intrados of the plane, having walls whose thicknesses vary according to the position of these cells relatively to the outline of the plane, the 20 various cells constituting the plane being fastened together by rivets or bolts which extend in directions perpendicular to the plane of flexure of the sustaining or steering plane.

25 With these and other objects in view, the invention consists in certain improvements and combinations and arrangement of parts, all as will be hereinafter described, the features of novelty being pointed out particularly in the claims at the end of this specification.

In the accompanying drawings—

Figure 1 represents diagrammatically, and in section on a plane perpendicular to the direction of spread thereof, a sustaining plane for aeroplanes constructed in accordance with the invention and

40 Figure 2 shows, a similar and somewhat modified form of sustaining plane embodying the present invention.

In constructing supporting planes for aeroplanes substantially as herein shown, it is preferable to employ a material which is both resistant to strains and is light in weight, metals such for instance, as aluminum, or its alloys, such as "duralumin" being particularly suitable.

45 The sustaining planes, as shown, are each made up of a suitable number of cells such as a , a^1 , a^2 , a^3 . . . a^{10} , formed of metal-sheets of appropriate width, and of a length

equal to the breadth of spread of the plane, the cells having such outlines that, when they are appropriately assembled they determine, by their external faces the outline to 60 be given to the surfaces of the plane, they produce preferably a plane the flight-edge and the lateral edges of which terminate in points.

The cell a which constitutes the attaching 65 edge of the plane is made, as shown in Fig. 1 of the drawing, of a single metal-sheet formed into an elongated cell and against a longitudinal side of this cell is fastened the next cell a^1 by means of rivets which pass 70 through the abutting longitudinal sides or walls of these cells. The remainder of the cells, a^2 — a^{10} which are to make up the plane are successively assembled and riveted or secured together with their longitudinal 75 sides in abutting relation in the same manner, care having been taken to give the metal-sheets composing the cells thicknesses which vary according to their position with respect to the outline of the sustaining-plane. 80

The ends of the metal-sheets, constituting the flight-edge, are fastened together by a row of rivets b , and the ends of the metal-sheets constituting the lateral edges (not shown) of the sustaining-plane may be similarly fastened together.

85 By constructing the plane of cells in substantially the manner above described, each cell is able to sustain its share of the flexing strains imposed on the plane.

90 Instead of constructing the sustaining plane as shown in Fig. 1, that is, of cells with solid walls on all sides, it may be constructed as shown substantially in Fig. 2 wherein similar cells are used having solid 95 walls on three sides thereof, the middle portion of the fourth longitudinal side or wall of the cell being omitted or cut away leaving downwardly and upwardly extending flanges or edges at its side, as shown, the cells being assembled in the manner substantially 100 as described in connection with Fig. 1, and the rivets or equivalent fastening devices being passed through these flanges or edges of one cell and the abutting wall of the next 105 adjacent cell.

110 Instead of forming the fourth longitudinal side of each cell with flanges or edges, as shown in Fig. 2, this side of each cell may be solid or closed, substantially as shown in Fig. 1, but provided with apertures.

2 It results from the present invention that, if the constituent cells or elements of the plane are properly constructed and assembled, a sustaining plane for aeroplanes 5 is obtained which is much preferable to those which comprise a covering upon a framework and which under exposure to vibrations are liable to become detached from the framework. Moreover, such plane 10 or wing coverings contributed only a small extent to the strength of the plane. The present invention, however, provides a plane the construction and assembling of which is easy and the assembled structure constitutes 15 a real wing-shaped beam of uniform resistance to flexing strains, and which, for these reasons, fulfilled satisfactorily the purpose aimed at. Furthermore a plane constructed according to this invention offers minimum 20 resistance to its forward movement, it presenting, in fact, as projecting parts only the heads of the rivets which fasten its lateral and flight-edges, and it may be made smooth over its entire surface by closing the crevices 25 at the joints between the cells, as, for example, by solder, and then enamelling the whole surface.

It is to be understood that the invention is in no manner restricted to the precise 30 constructions or applications herein shown or referred to, but it embraces, on the contrary, all equivalents thereof.

Having now described my invention, what I claim as new and desire to secure by Letters Patent is:

1. A sustaining or steering plane for aircraft comprising a plurality of elongated cells assembled side-by-side and fastened together, the upper and lower walls of the 40 cells constituting the upper and lower surfaces of the plane the longitudinal axis of each cell extending in the direction of the lateral spread of the plane, and each cell constituting a support of a flexing strength

capable of sustaining that portion of the 45 total load on the plane apportioned to such cell, whereby the elastic deflections of the individual cells under their respective portions of the total load will be substantially 50 equal.

2. A sustaining or steering plane for aircraft comprising a plurality of elongated cells extending side-by-side in substantial parallelism, two opposite sides of the cells forming the surfaces of the plane and other 55 opposite sides of the cells being in abutting relation with adjacent cells, and fastening devices located at points removed from the surfaces of the plane and extending in a direction transversely of the length of the 60 cells to secure the latter together.

3. A sustaining or steering plane for aircraft comprising a plurality of elongated cells assembled side-by-side and presenting 65 opposite sides which form the surfaces of the plane and other opposite sides which abut against adjacent cells, and securing devices extending through the abutting sides of adjacent cells in a direction transversely 70 of the length thereof and at points removed 75 from the surfaces of the plane.

4. A sustaining or steering plane for aircraft comprising a plurality of elongated cells assembled side-by-side and presenting 80 opposite sides which form the surfaces of the plane and other opposite sides which abut against adjacent cells, one of the latter sides presenting flanges which are directed toward one another to contact with the side of the adjacent cell, and securing 85 devices extending through the abutting sides of adjacent cells in a direction transversely of the length thereof and at points removed from the surfaces of the plane.

In testimony whereof I have hereunto set 85 my hand.

JEAN HUBERT.
